(57) **CLAIM**

The ornamental design for a calculator with clock, as shown and described.

DESCRIPTION

FIG. 1 is a top front perspective view of a calculator with clock in a lowered position, showing my new design;

FIG. 2 is a top plan view thereof;

FIG. 3 is a front elevational view thereof;

FIG. 4 is a bottom plan view thereof;

FIG. 5 is a rear end elevational view thereof;

FIG. 6 is a right side elevational thereof, the left side elevational view being identical thereto; and

FIG. 7 is a front elevational view showing the calculator with clock in a raised position;

FIG. 8 is a right side elevational view of the calculator with clock of FIG. 7, the left side elevational view being identical thereto;

FIG. 9 is a top plan view of the calculator with clock in the raised position;

FIG. 10 is a rear elevational view of a calculator with clock in the raised position;

FIG. 11 is a bottom plan view of the calculator with clock in the raised position; and,

FIG. 12 is a front perspective view of the calculator with clock in a raised position.

The broken line showing in FIGS. 2 and 7 is for illustrative purposes only and forms no part of the claimed design.
